UNITED STATES PATENT OFFICE.

REGINALD H. KNYVETT, OF NEW YORK, N. Y.

WRIST-WATCH.

1,309,988.

Specification of Letters Patent.

Patented July 15, 1919.

Application filed April 16, 1918. Serial No. 228,957.

To all whom it may concern:

Be it known that I, REGINALD H. KNYVETT, a subject of the King of England, residing at New York city, in the county of New 5 York and State of New York, have invented new and useful Improvements in Wrist-Watches, of which the following is a specification.

This invention relates to devices for supporting a watch on the wrist of the person, and its object is to provide a novel and improved support for the watch which is so constructed that the watch is effectually protected from breakage, exposure to the 15 elements, etc.

The object stated is attained by means of a combination and arrangement of parts to be hereinafter described and claimed, and in order that the same may be better understood, reference is had to the accompanying drawing forming a part of this specification.

In the drawing,

Figure 1 is a front elevation of the device; 25 Fig. 2 is a side elevation thereof, and Fig. 3 is a perspective view showing the device open to expose the watch.

Referring specifically to the drawing, 5 denotes the pocket or pouch of the conventional form in which is housed the watch 6. The pocket is open on one side to leave the face of the watch exposed, this opening being defined by an annular facing strip 7 having diametrically opposite outstanding 30 tongues 8 and 9, respectively. The tongue 8 is fitted with one of the members 10 of a pair of separable fasteners, such as ordinary glove clasps or snaps, the other member 11 of which is carried by another part to be 40 presently described.

The open side of the pocket 5 is provided with a cover 12 of leather or other suitable material, to protect the exposed face of the watch 6. The cover has an extension which 45 laps the tongue 9 and in the lapping parts are alined slots 13 through which is passed

the strap 14 by which the device is attached to the person's wrist. This strap also passes through a slot 15 in cover diametrically opposite the first-mentioned slots, and the two 50 ends of the strap are connected back of the cover by a buckle or other suitable adjustable strap fastening device 16. The slots are so positioned that the strap is attached to the cover clear of that portion of the latter 55 which closes the opening through which the watch is exposed, so that the cover may fit closely against the strip 7 and afford complete protection.

Where the strap 14 issues from the slot 15 60 is attached the clasp member 11, the same being secured to the outer face of the strap.

In use, the strap 14 is passed around the person's wrist and made fast by the buckle 16. The cover 12 is now next to the wrist 65 and the pocket 5 is next to the cover 12, with its open side facing the latter and covered thereby. The fasteners 10 and 11 being connected, the pocket is held snugly against the cover, and when it is desired 70 to view the watch, it is necessary only to disconnect the fasteners, which leaves the pocket free to be swung outward of the cover to expose the watch. The strap 14 provides a loose connection between the 75 pocket and the cover, so that the former may be swung as stated.

I claim:

A support for a wrist watch comprising a watch-supporting pocket open on one side 80 to expose the face of the watch toward the wrist, diametrically opposite outstanding tongues extending from the open side of the pocket, a cover for said side of the pocket, a wrist strap passing through the cover and 85 also through one of the tongues to provide a loose connection between the cover of the pocket, and separable fastener members on the other tongue and on the strap.

In testimony whereof I affix my signature. 90

REGINALD H. KNYVETT.
